Sam'l H. Ransom, of Albany, N. Y.
Letters Patent No. 1092, dated April 5, 1839.

The Schedule referred to in these Letters Patent and making part of the same,

To whom it may concern:

Be it known that I, Samuel H. Ransom of the City of Albany, State of New York, have produced a new original ornamental design for the plates of a Stove, which Stove is named the Russian, and I declare that the annexed delineations are full and accurate representations of the ornamented parts with their several ornaments. —

What I claim as my production and desire to secure by Letters Patent is the combination and arrangement of Ornamental figures and forms, represented in the accompanying drawings, forming together the ornamental design for the plates of a stove.
